(57) CLAIM

The ornamental design for a silicone cake pan, as shown and described.

DESCRIPTION

FIG. 1 is a front, left side, and top bottom perspective view of a silicone cake pan showing my new design.

FIG. 2 is a rear view thereof;

FIG. 3 is a top view thereof;

FIG. 4 is a right side thereof;

FIG. 5 is a left side view thereof;

FIG. 6 is a top plan view thereof;

FIG. 7 is a bottom view thereof; and,

FIG. 8 is a rear, bottom, and right side perspective view thereof.

The broken lines depict features of the silicone cake pan that form no part of the claimed design.
